UNITED STATES PATENT OFFICE.

LAWRENCE ROBBINS HANAVAN, OF KANSAS CITY, MISSOURI.

CLEANING AND POLISHING COMPOSITION.

1,235,136.

Specification of Letters Patent. Patented July 31, 1917.

No Drawing.

Application filed December 14, 1916. Serial No. 136,849.

To all whom it may concern:

Be it known that I, LAWRENCE ROBBINS HANAVAN, a citizen of the United States, residing at 2534 Montgall avenue, Kansas City, in the county of Jackson, State of Missouri, have invented a new and useful Cleaning and Polishing Composition, of which the following is a specification, to be known as "Hanavan's automobile and furniture polish."

My composition consists of the following ingredients combined in the proportions stated viz:—

15	Gasolene	3½ pints
	Japan drier	1 pint
	Varnish	½ pint
	Boiled linseed oil	1 pint
	Paraffin oil	1½ pints
20	Vinegar	½ pint

These ingredients are to be thoroughly mingled by agitation.

In using the above named composition remove all dust with a dry cloth apply 25. polish thoroughly then rub with a soft cloth

rubbing with the grain of the wood as much as possible.

By the use of the above composition it removes all dirt and grease and restores the life and original luster of furniture, piano 30 or automobile, cleans and polishes perfectly and leaves a dry lustrous surface free from streaks.

I claim:

1. The herein described composition of 35 matter consisting of gasolene, Japan drier, varnish, boiled linseed oil, paraffin oil and vinegar substantially as described and for the purpose specified.

2. The herein ~~described~~ composition of 40 matter for removing ~~dirt~~ and grease and polishing furniture and automobiles consisting of gasolene 3½ pints, Japan drier 1 pint, varnish ½ pint, boiled linseed oil 1 pint, ~~paraffin~~ oil 1½ pints, vinegar ½ pint, 45 substantially as described.

LAWRENCE ROBBINS HANAVAN.
